UNITED STATES PATENT OFFICE.

TRUE M. AVERY, OF GLENS FALLS, NEW YORK.

LIFTING JACK.

Application filed December 28, 1920, Serial No. 433,638. Renewed November 16, 1922.

To all whom it may concern:

Be it known that I, TRUE M. AVERY, a citizen of the United States, residing at Glens Falls, in the county of Warren and State of New York, have invented certain new and useful Improvements in Lifting Jacks, of which the following is a specification.

This application is a continuation of my application Serial No. 304,546 as to any 10 patentably novel subject matter broadly common to the two.

This invention relates to improvements in lifting jacks, proposing a construction especially useful for work in automobiles.

15 The principal objects of the invention, briefly stated, are to provide a small and compactly organized lifting jack capable of handling heavy loads and successfully withstanding severe stresses, having such organization that the operating parts are enclosed and fully protected and leakage of oil is prevented, which shall be exceptionally stable and well balanced, and which may be manufactured with facility and economy.

20 With the above objects in view the invention consists in certain features of structural detail and arrangement appertaining to the base structure of the jack and the arrangement within said base structure of the operating gearing.

An embodiment of the invention is illustrated in the accompanying drawing, wherein

25 Figure 1 is a vertical longitudinal section;

Figure 2 is a cross section on the line 2—2 of Fig. 1;

Figure 3 is a bottom plan view.

Similar characters of reference designate 30 corresponding parts throughout the views.

The improved jack comprises an operating screw 1 working within an upright casing 2 and co-operating with a nut 3, which travels lengthwise of said casing and is formed at the lower end of a hollow column 4 into which the screw projects, said column having at its upper end a supporting head 5 of suitable form for engagement with the axle or other object to be lifted. The screw 1 is 45 rotatably mounted and carries at its lower end a bevel gear 6 which is driven by a bevel gear 7 on a shaft 8 journaled in a tubular

bearing 9 formed as a lateral extension of the casing 2. The shaft 8 carries or is otherwise connected to a suitable operating handle (not shown). The nut 3 is non-rotatable and co-operates with the casing 2 as a guide, said casing and nut preferably having conforming square cross-sections. As the screw 1 is turned in either direction the 60 nut, and with it the head 5, is raised or lowered.

The jack constructed as above described is combined with the base and associated elements thereof which form the subject of 65 the present invention. The base includes an upper member or cover 10 and a lower member or bottom 11 secured in spaced relation to said cover. The interior of the base is completely enclosed and for this purpose one 70 of its essential parts, in this instance, the cover 10, is provided with vertical walls 12 delimiting a rectangular enclosure and extending between the cover and bottom. The screw 1 is supported on the bottom 11 and 75 turns on a suitable anti-friction bearing such as a ball member 13 provided on said bottom and operating in a recess suitably formed in the lower end of the screw.

The cover 10 and bottom 11 are companion 80 elements and according to the invention one of the companion elements is provided with lugs 14 which brace said elements to one another and also participate in their mutual connection. In the construction preferred 85 these lugs are cast integral with the cover 10 and walls 12, being arranged as internal abutments of said walls. Said lugs are preferably arranged at the sides and ends of the base. As shown the bottom 11 is connected to the lugs at the sides of the base by screws 15 which have threaded engagement with said lugs. The arrangement of the lugs, as described, enables the holes for the screw 15 to be of such depth as will 90 insure the strong connection of the bottom to the rest of the base structure. The lugs 14 also provide abutments against which the bottom is drawn and as shown and preferred, are of less depth than the walls 12 100 whereby the bottom may be fitted closely within said walls.

Having set forth my invention that which I claim as new and for which I desire

the protection of Letters Patent in the United States is:

In a lifting jack, an operating screw, a column enclosing said screw, and a hollow base for said column, said base comprising a cover, a bottom and vertical walls cast with the cover, and internal lugs cast with said

cover and walls, said bottom being fitted within said walls and against said lugs and being secured by screws to certain of said lugs, said lugs extending between said bottom and cover.

In testimony whereof I affix my signature.

TRUE M. AVERY.
